United States Patent

Des. 241,792
Patented Oct. 12, 1976

241,792

CHAIR

John C. Wehner, 103 Orchard St., Apt. 6,
Somerville, Mass. 02144

Filed Nov. 29, 1974, Ser. No. 528,254

Term of patent 14 years

Int. Cl. D6—01

U.S. Cl. D6—41

FIG. 1

FIG. 2

FIG. 3

FIG. 4

FIG. 5

FIG. 6

FIG. 1 is a front perspective view of a chair, showing our design;

FIG. 2 is a left side elevational view of the chair, the right side being a mirror image thereof;

FIG. 3 is a front elevational view of the chair;

FIG. 4 is a folded elevational view of the chair;

FIG. 5 is a rear elevational view of the chair; and

FIG. 6 is a front perspective view of a modified form of the chair.

I claim:

The ornamental design for a chair, as shown and described.
